(57) **CLAIM**

The ornamental design for an airtag protective shell, as shown and described.

DESCRIPTION

FIG. 1 is a front, left, and top perspective view of an airtag protective shell, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a bottom plan view thereof; and,

FIG. 8 is a top plan view thereof.

The broken lines shown in the drawings are included for the purpose of illustrating portions of the airtag protective shell that form no part of the claimed design.

1 Claim, 8 Drawing Sheets
